tion of New York

Application March 13, 1943, Serial No. 479,011

6 Claims.

(Cl. 74—282)

The present invention relates to powered gear drives and particularly to gear drives of the type employed in the propulsion of ships.

For many types of ship drives, the geared steam turbine has advantages over the old-style reciprocating steam engine or the turbine electric drive. For a given horsepower output, the geared steam turbine is lighter in weight and occupies less space. Moreover, it consumes less steam, and consequently less fuel, and requires less fuel storage capacity and a smaller boiler. With a geared steam turbine, then, it is possible to either save space for carrying extra cargo, or to use the space, which might otherwise be saved, for a larger size steam turbine, and increase the speed of the vessel, so that over a period of time it can transport a greater amount of cargo.

It has been the practice heretofore to use herringbone or double helical gears in geared steam turbine drives. The customary drive consists of a double herringbone reduction with the last reduction gear, or so-called "bull" gear, of extremely large size. Herringbone gears of large sizes take a long time to cut anyway because they have to be hobbed. In addition to this, however, it is difficult to harden them even by the flame hardening process, and consequently they usually have to be made from very hard steels, which do not require to be hardened after the teeth have been cut. The hard material increases the cutting time required, and it usually takes many days even weeks to cut a single herringbone "bull" gear for a ship propulsion unit.

The manufacture of this gear is one of the "bottle-necks" in ship production. Because of the difficulty of manufacturing these gears in the quantity required for war time needs, it has been necessary to use reciprocating steam engines and electric turbines in most cases for ship propulsion instead of the more desirable geared steam turbine.

One object of the present invention is to provide a drive suitable for a geared steam turbine propulsion unit, in which much smaller size gears may be used than those heretofore required. Such gears can be produced faster and in the quantities required for war-time shipping requirements.

A further object of the invention is to provide a geared steam turbine drive in which a herringbone gear may still be used as the "bull" gear but in which the size of this gear may be reduced considerably as compared with previous herringbone drives.

Another object of the invention is to provide

a drive, suitable for a geared steam turbine propulsion unit, from which herringbone and helical gears can be eliminated entirely, and in which bevel gears can be used instead.

Still another object of the invention is to provide a reduction drive in which part of the gearing of the drive may be used not only for a reduction but also as a bearing for supporting the bull gear, thereby eliminating the cost of the huge anti-friction bearings usually required for this purpose, and, moreover, conserving space.

Other objects of the invention are to provide a drive, suitable for a geared steam turbine propulsion unit, which will be more compact, require less space, and be easier to produce than drives heretofore used.

Still other objects of the invention will appear hereinafter from the specification and from the recital of the appended claims.

In the drive of the present invention, three reductions are used, but one of these reductions is a set of planetary gears. This construction permits of using relatively small gears in all of the reductions of the unit and, moreover, makes it possible to keep the unit quite compact. Preferably, the planetary is a bevel gear planetary, and preferably one side gear of the planetary is connected to the driven member of the second reduction, that is, the "bull" gear. The spider, which carries the planetary pinions, is then connected to the propeller shaft of the ship, while the other side gear of the planetary is secured in fixed position to the housing of the reduction unit.

The planetary provides a two to one reduction, and the further reduction required between the turbines and the propeller is attained by suitable selection of the ratios of the first and second reductions of the unit. The first and second reductions may be herringbone gears, but bevels are preferably used for these reductions also.

Bevel gears can be cut in much less time than herringbone, can easily be hardened by the flame hardening process, and can readily be lapped and ground so that extreme accuracy and extreme quietness in the drive can be obtained.

In one embodiment of the invention, there are two planetary gear units employed, one mounted at either side of the second reduction gear.

One side gear of each planetary is then connected to the second reduction gear, while one or both of the planetary spiders are connected to the propeller shaft. The other side gear of each planetary is fixed to the reduction housing. These latter side gears act then as bearings to

carry the planetaries, the "bull" gear and the propeller shaft. The planetaries are coaxial with the "bull" gear, and the whole makes a very compact unit.

Several different embodiments of the invention are illustrated in the accompanying drawings, in which:

Fig. 1 is a developed sectional view of a drive made according to one embodiment of this invention;

Fig. 2 is a view of the reduction unit of Fig. 1 in place in its housing, part of the housing and "bull" gear being broken away to show the second reduction pinions and, in section, the spider of the planetary, which is used for the third reduction;

Fig. 3 is a developed sectional view of a further embodiment of the invention, showing a drive in which two planetary units are incorporated and serve not only as a third reduction but as bearings for the "bull" gear of the second reduction and for one end of the propeller shaft; and

Fig. 4 is a sectional view of a still further embodiment of the invention, in which herringbone gears are used for the second reduction while two sets of bevel planetaries are used for the third reduction and for supporting the driven member of the second reduction and one end of the propeller shaft.

Referring first to the embodiment of the invention illustrated in Figs. 1 and 2, 10 and 11 denote, respectively, the prime mover shafts of the propulsion unit. These shafts are connected in any suitable manner to low pressure and high pressure steam turbines, respectively. The shaft 10 is journaled on suitable bearings 12 and 13 in a support 14. The shaft 11 is journaled on suitable bearings 16 and 17 in a support 18.

The shaft 10 carries a bevel pinion 21 at its inner end which meshes with a bevel gear 22 that is keyed or otherwise secured to a sleeve 23. The sleeve 23 is formed with a toothed face clutch member 24 at one end which engages with a toothed face clutch member 25 that is keyed or otherwise secured to a shaft 26. The sleeve 23 and shaft 26 are journaled in the casing 15 (Fig. 2) on suitable bearings 27, 28, 29 and 30.

The shaft 11 carries a bevel pinion 35 at its inner end which meshes with a bevel gear 36 that is keyed or otherwise secured to a sleeve 37. This sleeve 37 is provided with a clutch member 38 at its outer end which engages with a clutch member 39 that is keyed or otherwise secured to a shaft 40. Sleeve 37 and shaft 40 are journaled in the casing 20 on suitable bearings 41, 42, 43, and 44.

There is a spiral bevel pinion 50 integral with the shaft 26, and there is a spiral bevel pinion 51 integral with the shaft 40. These pinions mesh with a spiral bevel ring gear 52. This ring gear is secured to a fabricated hub member 54 which is rotatably mounted by means of suitable bearings 55 and 56 on a shaft 57.

There is a bevel gear 60 secured in any suitable manner to the hub member 54 to rotate therewith. This bevel gear constitutes one side gear of a bevel gear planetary. The pinions of this planetary are denoted at 61, and the other side gear of the planetary is denoted at 62. In the embodiment shown, there are six pinions 61. The pinions are journaled on suitable bearings 64 and 65 in a spider 66. They are secured against axial movement relative to the spider by plates 67 which are fastened to the spider by screws 68.

The spider 66 is keyed to the shaft 57, while

the side gear 62 is bolted or otherwise secured to the housing 70 for the gear unit. The casings 15 and 20 are fixedly mounted on this housing 70. The shaft 57 is coupled to the propeller shaft 71 of the ship by a toothed face clutch, one member 72 of which is keyed to the shaft 57 and the other member 73 of which is keyed to propeller shaft 71.

The ratios of the bevel gear reductions 21-22 and 35-36, respectively, are determined by the R. P. M. of the low pressure and high pressure turbines, respectively, which actuate the drive, and are so selected that the shafts 26 and 40 rotate at the same speed. The planetary unit 60, 61, 62 effects a 2 to 1 final reduction. The ratios of the bevel pinions 50 and 51 to the bevel gear 52 is determined in conjunction with the speed of the shafts 26 and 40 and in conjunction with the planetary unit 60, 61, 62 to give the desired R. P. M. on the propeller shaft of the ship. By using the planetary gears, the size of the gear 52 can be kept small as compared with the size of the "bull" gears used in conventional drives. Moreover, the drive is kept compact because the drive gear 60 of the planetary unit is connected directly to the driven gear 52 of the second reduction.

In the embodiment of the invention illustrated in Fig. 3, the two shafts, which are connected to the low pressure and high pressure turbines, are denoted at 80 and 81, respectively. The shaft 80 is journaled in the housing 82 on bearings 83 and 84. The shaft 81 is journaled in the housing 82 on bearings 85 and 86. The shaft 80 is formed at its inner end with a bevel pinion 88 which meshes with a bevel gear 89. This gear is keyed or otherwise fastened to a sleeve 90 that is provided with a toothed face clutch member 91 at its outer end. The clutch member 91 engages with a clutch member 92 that is keyed or otherwise secured to the shaft 93. The sleeve 90 and the shaft 93 are journaled in the housing 82, being mounted on suitable bearings 94, 95, 96, and 97. The shaft 81 has a bevel pinion 100 formed at its inner end which meshes with a bevel gear 101. The bevel gear 101 is keyed or otherwise secured to a sleeve 102. The sleeve 102 is formed at its outer end with a face clutch member 103 which engages with a face clutch member 104 that is keyed or otherwise secured to a shaft 105. The sleeve 102 and the shaft 105 are journaled in the housing 82 on bearings 106, 107, 108 and 109.

The shaft 93 has a spiral bevel pinion 110 integral with it, and the shaft 105 has a spiral bevel pinion 111 integral with it. These two pinions mesh with a spiral bevel ring gear 112. The ring gear 112 is bolted or otherwise secured to a fabricated hub member 114. The hub member 114 has two bevel gears 115 and 116 bolted or otherwise secured to it. These gears are coaxial with the ring gear 112 but are mounted on the hub member 114 at opposite sides of the ring gear 112. The two gears 115 and 116 are side gears of two bevel gear planetary reduction units.

The planetary unit of which the gear 115 is an element, comprises in addition to gear 115, a set of bevel pinions 117 and the bevel side gear 118. The planetary unit, of which the bevel gear 116 is an element, comprises in addition to the gear 116, a set of bevel pinions 120 and a bevel side gear 121.

The side gears 118 and 121 are fixedly secured in any suitable manner to the housing 82, and a shim 128 of suitable thickness may be interposed between the gear 121 and the housing to permit

adjusting the gears of the planetaries in proper engagement. The pinions 117 are journaled on suitable bearings 122 and 123 in a spider 124. The pinions 120 are journaled on suitable bearings 125 and 126 in a spider 127. The hub member 114 is journaled on the spiders 124 and 127, bushings 129 and 130, being provided for this purpose. The spider 124 is connected by a toothed face clutch, which is denoted as a whole at 132, with the propeller shaft 133. This shaft is coaxial with the spiders 124 and 127 and with hub member 114 and ring gear 112. One member of clutch 132 is formed integral with the spider 124 and the other member is keyed to the shaft 133. A similar clutch may be provided to connect the other spider 127 with the shaft 133, but preferably the spider 127 is mounted to rotate freely on the shaft 133. The drive to the shaft is transmitted, then, solely through the spider 124. The axial thrusts on the shaft 133 are taken by thrust bearings 135 and 136, which are mounted at either side of a thrust plate 137 that is secured by a nut 138 against a shoulder formed on the shaft 133. A shim 128 of suitable thickness may be interposed between stationary side-gear and the housing 82 to permit adjusting the planetary gears into proper mesh.

With the construction shown in Fig. 3, it will be seen that the spiders 124 and 127 support the propeller shaft 133, and these spiders are in turn supported by the stationary side gears 118 and 121 of the two planetary units, so that the two planetaries act, therefore, as bearings not only for the hub member 114 and ring gear 112, but also for the propeller shaft itself. Thus, need for separate radial bearings and the space required for these bearings, are eliminated.

The advantages of the present invention are not restricted to reductions employing bevel gears. It may be used also in drives employing other types of gears. Thus, Fig. 4 shows a drive built according to this invention in which one reduction consists of herringbone gears and the other reduction of a bevel planetary.

In Fig. 4, the shafts 140 and 141 correspond to the shafts 26 and 40, respectively, of the unit shown in Fig. 1, and to the shafts 93 and 105, respectively, of the unit shown in Fig. 3. The shafts 140 and 141, in other words, are driven from the low speed and high speed turbines, respectively, through suitable reductions, not shown. The shaft 140 has a herringbone pinion 142 formed integral with it, and the shaft 141 has a herringbone pinion 143 formed integral with it. These two pinions mesh at spaced points with a herringbone "bull" gear 145 to drive the same.

There are two bevel gears 146 and 147 secured in any suitable manner to opposite sides, respectively, of the herringbone gear 145 to rotate with the gear 145. These two gears 146 and 147 are side gears, respectively, of two bevel planetary units which are mounted at opposite sides of the herringbone gear 145. The planetary, of which the gear 146 is one element, comprises the bevel side gear 146, a set of bevel pinions 148, and the bevel side gear 149. The planetary, of which the bevel side gear 147 is one element, comprises the bevel side gear 147, a set of bevel pinions 150, and a bevel side gear 151.

The side gear 149 is bolted or secured in any other suitable manner to a plate 152, and this plate is secured in any suitable manner to the housing 153 of the reduction unit. The side gear 151 is bolted or otherwise secured to a plate 155, and this plate is also secured to the housing 153. 70

The side gears 149 and 151 are, therefore, stationary. Shims 154 and 156 may be interposed between the plates 155 and 152, respectively, to permit of positioning the gears of the two planetaries in proper engagement.

The planetary pinions 148 are journaled on studs 159 that are integral with a spider 157, and they are held in position on the studs by nuts 158. The spider 157 is keyed to the shaft 160. The 10 planetary pinions 150 are journaled on studs 161 that are integral with a spider 162, and they are secured on the studs by nuts 163. The spider 162 is connected to the shaft 160 by a clutch which is denoted as a whole at 164. One member of this 15 clutch is formed integral with the spider 162 and the other member is keyed to the shaft 160. The shaft 160 is connected to the propeller shaft of the ship by a clutch, one member of which is shown at 165. This clutch member 165 is keyed to the shaft 162.

With the construction shown in Fig. 4, it will be seen that the herringbone gear 145 is journaled on the spiders 157 and 162 by means of bushings 166 and 167. It will be seen, also, that since the side gears 149 and 151 are stationary, the planetary units operate as bearings for the ring gear 145, the shaft 160, and the planetary units themselves, and that, therefore, no radial bearings are required for mounting the shaft 160 or the ring gear 145.

In the embodiment of the invention shown in Fig. 4, both spiders 157 and 162 are connected to the shaft 160, but if desired, only one of these spiders need be connected thereto, as is the case 30 in the unit shown in Fig. 3. The other spider can then rotate freely on the shaft. The planetaries provide a 2 to 1 reduction between the shaft 160 and the ring gear 145. The result is that the size of the gear 145 can be cut in half as compared with the size of herringbone "bull" gears required in previous geared steam turbine drivers. It will be noted, too, that the two planetaries, being mounted directly at opposite sides of the "bull" gear 145, take up little space, and that the whole unit is quite compact. It will be seen, therefore, that with the construction of this invention, it is possible to get a much more compact drive than with previous constructions. The smaller size herringbone gears are, of course, much less expensive than the big herringbone gears heretofore required and can be cut in very much less than half the time required for the big gears.

It is not necessary to employ bevel gears in the planetary units of gear trains constructed according to the present invention. Spur gear planetaries may be used instead. In such event, as in the case of bevel planetaries, one of the gears of the planetary will be secured to the driven gear of the second reduction, and the other gear of the planetary will be fixed to the gear housing, while the pinions of the planetary will be mounted on a spider which is connected to the driven shaft. It will be understood, also, that while the invention has been described in connection with a turbine drive, it may be applied to other drives also. In fact, while several different embodiments of the invention have been illustrated, the invention is capable of further modification, and the present application is intended to cover any adaptations, uses, or embodiments of the invention following, in general, the principles of the invention and including such departures from the present disclosure as come within known or customary practice in the

gear art and as may be applied to the essential features hereinbefore set forth and as fall within the scope of the invention or the limits of the appended claims.

Having thus described my invention, what I claim is:

1. In a power drive, two shafts which are adapted to be connected to a low pressure and a high pressure turbine, respectively, a third shaft and a fourth shaft, reduction gearing for driving the third shaft from the shaft which is driven by the low pressure turbine, reduction gearing for driving the fourth shaft from the shaft which is driven by the high pressure turbine and at the same speed as the third shaft, a fifth shaft, a gear journaled coaxially thereof for rotation relative thereto, two identical pinions secured to the third and fourth shafts, respectively, and meshing with said last named gear at spaced points around its periphery to drive said last named gear on rotation of the third and fourth shafts, and a planetary reduction gearing mounted coaxially on the fifth shaft for driving the fifth shaft from said last named gear, one member of said planetary being secured to said last named gear, another member of said planetary being fixed against rotation, and the pinions of said planetary being connected to said fifth shaft.

2. In a power drive, two shafts which are adapted to be connected to a low and a high pressure turbine, respectively, a third shaft and a fourth shaft, a set of bevel gears for driving the third shaft from the shaft which is driven by the low pressure turbine, a second set of bevel gears for driving the fourth shaft from the shaft which is driven by the high pressure turbine and at the same speed as the third shaft, a fifth shaft, a bevel ring gear journaled coaxially thereof and rotatable relative thereto, a bevel pinion secured to each of the third and fourth shafts and meshing with said bevel ring gear at spaced points around its periphery to drive the bevel ring gear from the third and fourth shafts, said bevel pinions being identical, and a set of bevel planetary gears, which are mounted coaxially of the fifth shaft, to drive the fifth shaft from said bevel ring gear, said planetary set comprising a pair of bevel side gears, a bevel pinion which meshes with both of said side gears, and a spider on which the pinion is rotatably mounted, one bevel side gear of the planetary being secured to said bevel ring gear, the other bevel side gear of the planetary being fixed against rotation, and the spider of the planetary being secured to said fifth shaft.

3. In a power drive, a driven gear, a shaft mounted coaxially of the driven gear but rotatable independently thereof, and two sets of planetary reduction gearing mounted on either side of said driven gear coaxially of said shaft, one gear of each planetary set being connected to said driven gear to rotate therewith, another gear of each planetary set being rigidly fixed against rotation, a spider for each planetary set mounted coaxially of said shaft, the pinions of each planetary set being mounted rotatably on the spider of the set to mesh with the side gears

of said set, one of said spiders, at least, being connected to said shaft to rotate said shaft on rotation of said driven gear, and said driven gear being journaled on said spiders.

4. In a power drive, a driven gear, and two sets of bevel planetary gearing mounted at opposite sides, respectively, of said driven gear, one bevel side gear of each set being connected to said driven gear to rotate therewith, the other bevel side gear of each set being rigidly fixed against rotation, a rotatable spider for each set, the bevel pinions of each set being rotatably mounted on the spider to mesh with the side gears of the set, a shaft mounted coaxially of the two spiders and the driven gear, one of the spiders, at least, being connected to said shaft to rotate said shaft on rotation of the driven gear, and said driven gear being journaled on the two spiders.

5. In a power drive, two shafts which are adapted to be connected to a low and a high pressure turbine, respectively, a third shaft and a fourth shaft, a set of bevel gears for driving the third shaft from the shaft which is driven by the low pressure turbine, a second set of bevel gears for driving the fourth shaft from the shaft which is driven by the high pressure turbine at the same speed as the third shaft, identical bevel pinions secured to the third and fourth shafts, a bevel ring gear with which said last named pinions mesh at the spaced points around its periphery, two sets of bevel planetary gearing which are mounted at opposite sides of said bevel ring gear, one of the bevel side gears of each planetary set being secured to said ring gear to rotate therewith, the other bevel side gear of each planetary set being fixed against rotation, a spider for each planetary set, the bevel pinions of each planetary set being rotatably journaled on the spider of the set to mesh with the side gears of the set, said driven gear being journaled on the two spiders, and a shaft to which one of the spiders, at least, is secured, said shaft being mounted coaxially of the driven gear and of the two sets of planetary gears.

6. In a power drive, two shafts which are adapted to be connected to a low pressure and a high pressure turbine, respectively, a third shaft and a fourth shaft, reduction gearing for driving the third shaft from the shaft which is driven by the low pressure turbine, reduction gearing for driving the fourth shaft from the shaft which is driven by the high pressure turbine and at the same speed as the third shaft, a fifth shaft, two identical pinions secured to the third and fourth shafts, a driven gear with which the two last named pinions mesh at spaced points around its periphery, and two sets of planetary reduction gearing mounted coaxially of the fifth shaft, each of said two planetary sets comprising two gears, a spider, and a pinion rotatably mounted on the spider and meshing with both of the gears of the set, one of the gears of each set being secured to said driven gear and the other gear of each set being fixed against rotation, and the spider of at least one set being secured to the fifth shaft, said driven gear being journaled on the two spiders.

FREDERICK E. McMULLEN.
